COMBINED SLIDE NECKTIE AND PENCIL

Robert A. Klitzner, Cranston, R. I.

Application August 12, 1957, Serial No. 47,340

Term of patent 14 years

(Cl. D3—16)

Fig. 1 is a front elevational view of a combined slide necktie and pencil, showing my new design;

Fig. 2 is a perspective view, on enlarged scale, of the pencil end as it appears detached from the necktie; and

Fig. 3 is a rear perspective view of the slide member as it appears detached from the necktie.

I claim:

The ornamental design for a combined slide necktie and pencil, substantially as shown.
